(57) **CLAIM**

The ornamental design for a door facing, as shown and described.

DESCRIPTION

FIG. 1 is a front perspective view of a first embodiment of a door facing according to my new design;

FIG. 2 is a front elevational view of the door facing of FIG. 1;

FIG. 3 is a rear elevational view of the door facing of FIG. 1;

FIG. 4 is a top view of the door facing of FIG. 1;

FIG. 5 is a bottom view of the door facing of FIG. 1;

FIG. 6 is a cross-sectional view taken along the line 6-6 of FIG. 2;

FIG. 7 is a cross-sectional view taken along the line 7-7 of FIG. 2;

FIG. 8 is an enlarged view of the encircled portion shown in the circle "8" in FIG. 6;

FIG. 9 is an enlarged view of the encircled portion shown in the circle "9" in FIG. 7;

FIG. 10 is a cross-sectional view taken along the line 10-10 of FIG. 2;

FIG. 11 is a left side view;

FIG. 12 is a right side view;

FIG. 13 is a cross-sectional view taken along the line 13-13 of FIG. 2;

FIG. 14 is a front perspective view of a second embodiment of a door facing according to my new design;

FIG. 15 is a front elevational view of the door facing of FIG. 14;

FIG. 16 is a rear elevational view of the door facing of FIG. 14;

FIG. 17 is a top view of the door facing of FIG. 14;

FIG. 18 is a bottom view of the door facing of FIG. 14;

FIG. 19 is a cross-sectional view taken along the line 19-19 of FIG. 15;

FIG. 20 is a cross-sectional view taken along the line 20-20 of FIG. 15;

(Continued)

FIG. 21 is an enlarged view of the encircled portion shown in the circle “21” in FIG. 19;
 FIG. 22 is an enlarged view of the encircled portion shown in the circle “22” in FIG. 20;
 FIG. 23 is a cross-sectional view taken along the line 23-23 of FIG. 15;
 FIG. 24 is a left side view of the door facing of FIG. 14;
 FIG. 25 is a right side view of the door facing of FIG. 14;
 FIG. 26 is a cross-sectional view taken along the line 26-26 of FIG. 15;
 FIG. 27 is a front perspective view of a third embodiment of a door facing according to my new design;
 FIG. 28 is a front elevational view of the door facing of FIG. 27;
 FIG. 29 is a rear elevational view of the door facing of FIG. 27;
 FIG. 30 is a top view of the door facing of FIG. 27;
 FIG. 31 is a bottom view of the door facing of FIG. 27;
 FIG. 32 is a cross-sectional view taken along the line 32-32 of FIG. 28;
 FIG. 33 is a cross-sectional view taken along the line 33-33 of FIG. 28;
 FIG. 34 is an enlarged view of the encircled portion shown in the circle “34” in FIG. 32;
 FIG. 35 is an enlarged view of the encircled portion shown in the circle “35” in FIG. 33;
 FIG. 36 is a cross-sectional view taken along the line 36-36 of FIG. 28;
 FIG. 37 is a left side view;
 FIG. 38 is a right side view;
 FIG. 39 is a cross-sectional view taken along the line 39-39 of FIG. 28;
 FIG. 40 is a front perspective view of a fourth embodiment of a door facing according to my new design;
 FIG. 41 is a front elevational view of the door facing of FIG. 40;
 FIG. 42 is a rear elevational view of the door facing of FIG. 40;
 FIG. 43 is a top view;
 FIG. 44 is a bottom view;
 FIG. 45 is a cross-sectional view taken along the line 45-45 of FIG. 41;
 FIG. 46 is a cross-sectional view taken along the line 46-46 of FIG. 41;
 FIG. 47 is an enlarged view of the encircled portion shown in the circle “47” in FIG. 45;
 FIG. 48 is an enlarged view of the encircled portion shown in the circle “48” in FIG. 46;
 FIG. 49 is a cross-sectional view taken along the line 49-49 of FIG. 41;
 FIG. 50 is a left side view;
 FIG. 51 is a right side view;
 FIG. 52 is a cross-sectional view taken along the line 52-52 of FIG. 41;

FIG. 53 is a perspective view of a fifth embodiment of a door facing according to my new design;
 FIG. 54 is a front elevational view thereof;
 FIG. 55 is a perspective view of a sixth embodiment of a door facing according to my new design; and,
 FIG. 56 is a front elevational view thereof.
 The dot-dash broken line circles depict limits of the enlarged views and form no part of the claimed design.
